UNITED STATES PATENT OFFICE.

ALFRED ZÖLLER, OF CHARLOTTENBURG, NEAR BERLIN, GERMANY.

ELECTRIC LAMP.

Application filed November 10, 1916, Serial No. 130,674, and in Germany November 1, 1913.

(GRANTED UNDER THE PROVISIONS OF THE ACT OF MARCH 3, 1921, 41 STAT. L., 1313.)

Incandescent lamps, especially metallic filament lamps, have the disadvantage that the inner faces of the glass bulb turn black after a time. This defect is mainly shown 5 by the so called half-watt-lamps; these are lamps with a coiled filament glowing in an inert gas such as nitrogen or the like.

This invention relates to an improvement of the last-mentioned class of lamps. Its 10 main object is to arrange a cooling-chamber suitably spacious in comparison with the filament chamber, in such a manner that it cannot be directly struck by the direct rays of the incandescent body. This may be effected, for instance, by a reflecting shield 15 preventing the direct rays from reaching the cooling chamber, but allowing the hot gases to flow from the filament chamber to the cooling chamber and back again. The 20 shield, besides, may be used as a carrier for the filament, as it is well known. Moreover, it is possible to enlarge the cooling-chamber in the horizontal plane, so that no rays may get to the cooling-chamber.

The improvement of this invention, in 25 comparison with the known arrangements consists in the fact that the temperatures of the filament chamber and the cooling chamber are more different from one another 30 than hitherto, in consequence of which the evaporated and thrown-off parts are more intensively cooled and deposited than hitherto.

The main object of this invention is to construct the filament chamber in such a manner 35 that only a few vapours condense on its inner side, or, that the inner sides are only a little covered with the condensed gas.

In the accompanying drawings, wherein 40 corresponding parts are represented by like characters in the various views,

Figure 1 shows a lamp of low candle power and provided with a small cooling chamber;

Figure 2 shows a lamp of high candle power and provided with a large cooling chamber extending in a vertical plane;

Referring to the drawing in detail, *a* is the filament arranged in the lamp chamber *b*; *c* is the cooling chamber, on the in-

side of which the gases condense. *d* is a shield made of metal, black glass or the like and, if desired, it may be provided with a mirror preventing the radiating heat from going to the cooling-chamber and also acting to deflect the rays of light in the desired direction and thus it serves as a reflector. The shield *d* lies within the lamp chamber *b* and is arranged adjacent the point of communication between the lamp and cooling chambers.

A better cooling effect in the cooling-chamber of the above-mentioned lamps may also be attained by surrounding the chamber with a cooling good heat conducting lining of large surface. The large surface may be obtained by providing the said lining with cooling ribs or pipes constructed inside or outside the lamp. Preferably also the lamp socket is formed as a cooling-lining for the cooling chamber. By this arrangement, as suggested in Fig. 1, not only a more intensive cooling and, consequently, a more rapid condensation of the vapours is effected, but also the bases of the lamp 75 in the glass bulb are kept cool.

According to the present invention an improved cooling effect is obtained by providing cooling ribs or pipes extending either in a horizontal or in a vertical plane. The 80 cooling chamber of the lamp, however, may also be provided with cooling ribs inside or outside thereof, by means of which the conduction of the heat is substantially increased.

Further the outer globe may be surrounded by a strong wire-net or may be made itself of wire-glass.

It will be understood that I do not limit myself to the details of construction above 90 set forth, and that many modifications may be made within the scope of my invention.

What I claim, and desire to secure by Letters Patent of the United States, is as follows:

1. In a gas filled metallic filament electric lamp, a closed globe having a filament chamber, and a metallic filament therein, a cooling chamber, a screen arranged above the filament within the filament chamber and 100

adjacent the point of communication between the filament chamber and the cooling chamber, said screen being so arranged so as to afford ample space for free circulation of hot gases from the filament chamber to the cooling chamber, whereby the gas vapors condensed in the cooling chamber are deposited on the walls of the latter, and a metallic jacket of relatively high heat con-

ductivity associated with the cooling chamber. 10

2. A gas filled metallic filament electric lamp as claimed in claim 1 characterized by the fact that the lamp cap is extended downwardly over the cooling chamber. 15

In testimony whereof I affix my signature.

ALFRED ZÖLLER.
